UNITED STATES PATENT OFFICE

WALTER R. SHUGERT, OF HUNTINGDON, PENNSYLVANIA

ELECTRIC SOCKET

Application filed October 29, 1931. Serial No. 571,899.

The invention relates to certain new and useful improvements in electric sockets and the primary object of this invention is to provide a socket of the character above mentioned that is exceedingly simple in construction, can be manufactured and sold at a nominal cost, is pleasing in appearance and is otherwise well adapted for the purpose intended.

10 The invention consists in the novel form, construction and arrangement of parts shown in the accompanying drawing, herein described in detail, and particularly pointed out in the appended claim.

15 In the drawing:

Figure 1 is an elevational view of the socket.

Figure 2 is a longitudinal sectional view therethrough.

20 Figure 3 is a bottom plan view of the socket.

With reference more in detail to the drawing, it will be seen that the socket comprises a substantially cylindrical body 5 provided 25 at one end with an axial recess or socket 6, and at a relatively opposite end with a reduced threaded portion or pin 8. A dome-shaped cap 9 is also provided and the same is internally threaded for threaded reception 30 of the pin 8. Preferably, the body 5 and the cap 9 are formed from the same material, and preferably of a suitable composition.

35 The cap 9 in the top thereof is provided with an opening 10 through which is passed into the cap, one end of an electric cord 11 and the wires 12 of the cord are secured to the eyes of eye bolts 13 that extend longitudinally through the solid portion of the

40 body and serve as binding posts. At their free ends, the eye bolts 13 extend into the socket or recess 6, and at said end are threaded. The threaded end of one of the eye bolts has screwed thereto the shank or plate portion 14 of a resilient contact member 15, the contact member 15 being formed of resilient metal and preferably bent upon itself somewhat in the form of a U.

45 The threaded end of the remaining eye bolt 13 is threaded through an aperture pro-

vided in a flange 16 formed at the inner end of a metallic sleeve 17 that is arranged within the recess 6, and is corrugated or otherwise formed to provide screw threads 18.

As is thought apparent, the threaded sleeve 17 serves to couple a plug on one end of a second electric cord, with the plug of my invention or to electrically connect the threaded stem of an electric bulb with the socket of my invention, it being apparent that the stem of the electric bulb will be threaded axially and inwardly of the sleeve 18 so that the contact member of the bulb will engage the spring contact 15.

From the foregoing it will be seen that I have devised a simple and inexpensive electric plug, and to disassemble the parts of the same it is apparent that cap 9 may be easily removed from the body, and the eye bolts 13 rotated so as to disengage the respective eye bolts from the contact 15 and the sleeve 18 whereby said sleeve and contact may be removed from the recess 6. Manifestly the parts may be readily reassembled, sleeve 18 and contact member 15 being first properly positioned in the socket, after which the eye bolts 13 may pass through the body threadedly engaged with the contact 15 and sleeve 18 respectively, the wires 12 of the cord 11 being connected with the eyes of the eye bolt and finally the cap 9 shifted longitudinally relative to the cord 11 and then screwed on to the end or stem 8 of the body completing the assembly.

To hold cap 9 and body 5 against casual rotation relative to one another, pins 7 have headed ends embedded within the cap, and free end portions arranged to engage the body 5.

Even though I have herein shown and described the preferred embodiment of the invention, it is to be understood that the same is susceptible of further changes, modifications and improvements coming within the scope of the appended claim.

Having thus described my invention, what I claim as new is:

An electrical socket comprising a substantially cylindrical body of composition material having at one end a socket chamber,

and at a relatively opposite end being reduced in diameter and externally threaded to provide a pin, a pair of terminal bolts extending through the body and having threaded ends terminating within said socket chamber, a threaded sleeve of conducting material arranged in the socket chamber and provided at one end with a flange having an aperture with which is threadedly engaged 5 one of said terminal bolts, a substantially U-shaped spring contact member having an apertured portion threadedly engaged with the other of said bolts and arranged at the inner end of said socket, and a dome-shaped 10 cap of composition material provided with internal threads and having screw threaded engagement with said pin, said contact bolts having heads extending interiorly of said cap, and said cap having an aperture in the 15 top thereof to accommodate an electric cord.

In testimony whereof I affix my signature.

WALTER R. SHUGERT.
